UNITED STATES PATENT OFFICE.

JAMES C. FARMER, OF RADFORD, VIRGINIA.

SAFETY DEVICE.

Application filed June 13, 1923. Serial No. 645,133.

To all whom it may concern:

Be it known that I, JAMES C. FARMER, a citizen of the United States, residing at Radford, in the county of Montgomery and 5 State of Virginia, have invented a new and useful Safety Device, of which the following is a specification.

This invention has reference to railway crossing gates, and more particularly to 10 gates of this character which are electrically controlled, the controlling mechanism being such as to close a gate at a railway crossing upon the approach of a train, and to automatically move the gate to its open 15 position after the train has passed the road intersecting the railroad tracks.

An important object of the invention is to provide a gate construction including a 20 pair of vertically movable arms, the arms being supported in such relation with the road surface as to completely block passage thereover.

Another object of the invention is to provide means to cause the arms to move gradually to their active and inactive positions, 25 thereby eliminating any possibility of injuring persons or vehicles passing in proximity to the gate while the same is in motion.

30 A still further object of the invention is to provide a stop signal automatically controlled by the movement of the gate to indicate to persons that the gate is about to be moved to its active position.

35 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

45 Referring to the drawings:

Figure 1 is a diagrammatical view disclosing the gate controlling circuits.

Figure 2 is an elevational view disclosing the gate supporting post in section.

Figure 3 is a vertical sectional view through the upper portion of the gate supporting post and taken on line 3—3 of Figure 2.

50 Figure 4 is a sectional view through the

base of the supporting post taken on line 4—4 of Figure 2.

Figure 5 is a sectional view taken on line 5—5 of Figure 3.

Figure 6 is a sectional view taken on line 6—6 of Figure 3.

Referring to the drawings in detail, the reference character 5 designates the rails of a railway track, and the reference character 6 designates a road surface intersecting the track.

The gate construction includes a hollow base 7 which is formed with an upwardly extended annular flange 8 designed to receive the lower extremity of the gate supporting pipe 9. At the upper end of the pipe 9 is a housing 10 which is box-like in formation and has its upper extremity closed by means of the removable cover 11. The side walls 12 of the housing are 75 formed with cut out portions to accommodate transparent sections 13 through which the movable signal, to be hereinafter more fully described, may be readily viewed.

A flange 14 is formed integral with one 80 wall of the base 7 and is provided with an opening to accommodate the hollow shaft 15 that is formed with a beveled pinion 16 at the upper end thereof, the beveled pinion meshing with the teeth of the pinion 17 85 supported on one end of the rotor shaft 18, so that upon rotary movement of the shaft, the pinions 17 and 16 will be rotated.

The shaft 15 is provided with internal threads to cooperate with the threads 19 90 of the operating shaft 20 whereupon rotary movement of the pinion 16 will cause a vertical movement of the shaft 20.

As shown, the upper extremity of the shaft 20 operates through the bearing 21 95 and has connection with the link 22 which in turn has pivotal connection with the arm 23 on which one of the gate arms 24 is mounted, the inner extremity of the arms 24 being provided with cooperating teeth 100 to cause a movement of the arms simultaneously when the arm to which the power is directed, has been moved.

Openings 25 are provided in the side walls of the pipe 9 and provide clearances for the 105 adjacent inner ends of the arms 24. Supporting arms 26 are secured within the pipe 9 and are disposed in spaced relation with each other, the supporting arms being formed with openings to accommodate the 110

shafts 27 that in turn support the arms 24.

Pivottally connected with the arm 23 is a connecting link 28 that has its upper end pivottally connected between the spaced ears

5 29 depending from the movable signaling member 30. This movable signaling member includes a frame formed of grooved bars 31 that receive the transparent members 32 on which suitable indicating characters 33 may be provided so that when the signaling member is moved downwardly, the indicating characters will be displayed through the transparent members 13 indicating to persons traveling in proximity to

10 15 the signal that the road is closed.

Guide rods 33 are positioned within the housing 10 over which guide rods the signaling member moves to accomplish its purpose. Supported at the upper portion of the 20 signaling member is a bar 34 that supports the socket 35 in which the lamp 36 is positioned, wires 37 being in circuit with the lamp to supply electric energy thereto, eliminating the interior of the housing 10 at all 25 times.

In order that the arms 24 may be clearly visible, openings 37 are provided in the end walls 38 of the housing 10, which openings permit the light rays from the lamp 36 to 30 be projected laterally onto the arms 24.

Mounted within the base 7 is a motor indicated at 39 which is in circuit with a suitable source of electric supply, through the wire 40, which wire are in circuit with 35 the switch members 41 and 42 so that when the switch members are moved into cooperative relation with each other, a circuit is completed to the motor causing the same to operate the pinion 16 in a manner as described to move the shaft 20, longitudinally 40 of the pipe in which the same is supported.

Mounted within the pipe 9 are spaced 45 switch members 43 and 44, which switch members are of the spring finger type between which the blade 45 is adapted to move, the blade 45 being pivottally supported at 46 within the pipe 9 the rear end thereof lying in the path of travel of the pins 47 that extend laterally from the operating 50 shaft 20. A coiled spring 48 has connection with the blade 45 at one end thereof, the opposite end of the coiled spring being anchored to the wall of the pipe 9, in direct alignment with the pivot point 46 of the 55 blade so that as the ends of the blade are moved out of alignment with the pivot point 46 thereof, the spring will act to snap the knife blade into engagement with one of the switch members.

60 In the operation of the device, assuming that a train is moving over the track in the direction of the arrow in Figure 2 of the drawings. As the train wheels contact with the switch member at the right of the showing in Figure 2 of the drawings, the circuit

will be completed to the motor 49 causing the same to operate, which in turn rotates the pinion 16 to rotate the shaft 20 and move the same downwardly.

As the shaft 20 moves downwardly the 70 arm 23 is also moved, moving the arms 24 upwardly to their active positions. Simultaneous with the movement of the arms 24 to their active positions, the signaling members moves downwardly to display the indicating characters carried thereby, before the transparent members 13. Upon downward movement of the shaft 22 the uppermost pin 47 contacts with the knife blade 45 causing the same to move into engagement with the 80 switch member 43. The circuit to reverse the operation of the motor 39 is now partially closed through the wire 50 that is in circuit with the switch member 43, but since the switch member at the left hand end of Figure 2 of the drawings is open, the circuit to the motor to reverse the same is not closed until the train passing over the rails contacts with the switch member 42 to cause the same to move into engagement with the 85 switch member 41 whereupon the motor is operated in the opposite direction, resulting in a reverse movement of the shaft 20 to move the gate arms 24 and the signaling member to their normal positions.

It might be further stated however that the motor 39 is in circuit with the switch member 41 through the wire 51 and the motor is in circuit with the switch member 44 through the wire 52.

90 What is claimed as new is:

1. In a railway crossing signal, a supporting member, a housing disposed at the upper end of the supporting member and having guide members, a movable signaling member operating in the housing, a shaft supported in the supporting member, means for moving the shaft vertically in the supporting member, means for connecting the shaft to the signaling member to cause the signaling member to move within the housing, and a pair of vertically movable arms operated by the movement of the shaft.

vertical movement of the signaling member, said housing having lateral openings, movable arms mounted on the supporting member, the lateral openings of the housing permitting light rays to illuminate the movable arms, and means within the supporting member for moving the arms and signaling members simultaneously.

4. In a railway crossing signal, a supporting member, a housing mounted at the upper end of the supporting member, a movable signaling member within the supporting member, a motor disposed at the base of the supporting member, means associated with the motor and having connection with the signaling member for moving the signaling member into and out of operation, a pair of swinging arms mounted on the supporting member, and means having connection with the signal member operating means for simultaneously moving the arms and signaling member.

5. In a railway crossing signal, a hollow supporting member, a housing at the upper end of the hollow supporting member, and having portions of the side walls thereof formed of transparent material, a signaling member movable within the housing, to display signals through the transparent portions of the housing, vertically movable means within the housing and engaging the signaling member for moving the signaling member within the housing, a pair of swinging arms having teeth formed on their adjacent ends, said teeth adapted to mesh to cause a movement of the arms simultaneously and means connecting the arms and

the signaling member to move the arms and signaling member simultaneously.

6. In a railway crossing signal, a supporting member, a housing mounted at the upper end of the supporting member, a signaling member in the housing, a pair of swinging arms mounted on the supporting member, a motor positioned at the base of the supporting member, means connecting the motor, swinging arms and signaling member for simultaneous movement, a pair of switch members for controlling the circuit to the motor, and an automatically operated switch member in circuit with the first mentioned switch members for controlling the circuit to the first mentioned switch members.

7. In a railway crossing signal, a hollow supporting member, a housing mounted at the upper end of the supporting member, a signaling member in the housing, a pair of swinging arms having their adjacent ends extending into the hollow supporting member, means engaging the arms and having engagement with the signaling member to move the arms and signaling member simultaneously, and electrically controlled means for controlling the movement of the signal and arm moving means.

In testimony that I claim the foregoing as my own, I have hereto affixed my signature in the presence of two witnesses.

JAMES C. FARMER.
